UNITED STATES PATENT OFFICE.

MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,105,563.

Specification of Letters Patent. Patented July 28, 1914.

Application filed August 10, 1911. Serial No. 643,336.

To all whom it may concern:

Be it known that I, MORTON L. JOHNSON, a citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and has for its object the provision of such a system that is especially adapted to a comparatively small number of telephone lines extending to an exchange and my invention is of special utility in connection with private branch exchanges though it is not to be limited to this use.

In practising my invention I preferably employ as many link connectors as are required to take care of the busy hour of the exchange. Each of these link connectors has a plurality of connecting switches, preferably but one for each line centering at the exchange. Where a single switch for each line per link connector is employed such switch is desirably capable of effecting the operator's telephone connection with the line to which such switch is individual, when such line is a calling line, and which is capable of effecting the association of a source of ringing or signaling current with the line to which it is individual, when such line is a called line.

The telephone exchange system of my invention preferably includes means whereby a link connector is limited to telephonic connection with two telephone lines at a time. This feature of my invention is desirably embodied in an equipment by which all switches of a link connector that is employed for connecting two lines in conversation, except the two switches that enable this link connector to perform its function, are mechanically prevented from effecting connection of their lines with such link connector when already in service in connecting a calling and called line, though I do not desire to be limited to the prevention of the operation of switches for this purpose.

My invention has for a further object the provision of means whereby the intrusion of an operator into an established circuit is guarded against to prevent the operator from listening in, whereby the system of

my invention is rendered secret, though I do not limit myself to this characteristic. As I have organized my invention I mechanically prevent the inclusion of an operator's telephone in connection with a link that is serving to connect two lines and I further employ means for electrically preventing the effective connection of an operator's telephone with two connected lines when the operator seeks to effect the connection of her telephone with such two connected lines with the aid of two link connectors. In the first instance the switches associated with the same link connector and individual to the connected lines jointly serve to prevent the operation of the listening switch to connect the operator's telephone in circuit with the connected lines and in the second instance switches of two link connectors that the operator seeks to employ for connecting her telephone in an established connection jointly serve to prevent such connection of the operator's telephone. I do not wish to be limited, however, to the mechanical and electrical means, as specified, for preventing the association of the operator's telephone with an established connection.

In accordance with another feature of my invention I provide supplemental listening keys individual to the telephone lines and provide means whereby none of these listening keys may be operated to include an operator's telephone in circuit with connected lines. The system of my invention also includes means to prevent a third line from becoming connected in any way with connected lines.

There are other objects and advantages of my invention which I will not set forth in this introduction but which will more fully appear by reference to a preferred embodiment of my invention shown in the accompanying drawings in which—

Figures 1 and 2 collectively constitute a diagrammatic illustration of a system equipped in accordance with the invention, the right hand end of Fig. 1 to be joined with the left hand end of Fig. 2 in reading these figures; Fig. 3 is a diagrammatic view illustrating mechanism for automatically effecting the extension of a telephone line that may enter into the system of my invention, the line illustrated being a well known automatic telephone line; Fig. 4 is a plan view of a portion of switching mecha-

nism which I preferably employ; Fig. 5 is an end view, somewhat diagrammatic, of switching mechanism which I preferably employ; Fig. 6 is a view similar to Fig. 5 except that the parts occupy another position preparatory to their restoration to normal; Fig. 7 is a view on line 77 of Fig. 5; and Fig. 8 is a side view of a manually operated restoring key.

10 Like parts are indicated by similar characters of reference throughout the different figures.

In Figs. 1 and 2 I have shown three telephone lines that extend to the private branch exchange, one of these telephone lines being in the form of a trunk 1 extending from another exchange diagrammatically indicated at 2 where one of many link connectors is illustrated for connecting the trunk line 1 with a telephone line extending to the exchange at 2, as for instance, from a substation A, all as is well known by those skilled in the art, on which account the apparatus illustrated at 2 and A will not be specifically described. Another telephone line 3 is illustrated as extending from a manual exchange subscriber's station B. A telephone line 4 extends from a manual exchange subscriber's station C. The telephone line 1 is shown as provided with two switching devices preferably in the form of keys 5 5, two keys being shown as there are but two link connectors shown as will appear, each key 5 being individual to a link connector. The telephone line 3 is provided with two keys 6 individual to said link connectors and the telephone line 4 is provided with keys 7 individual to the link connectors. One of the link connectors proper includes the two talking strands 8 8. The other of the two illustrated link connectors includes the talking strands 9 9. The keys 5, 6 and 7 each includes a pair of lever springs 10 that are connected with the sides of the lines to which the keys of which springs 10 form parts are individual. The normally open contacts of the springs 10 of the keys 5, 6, and 7 to which the link connector 8 is common are connected with the side of this link connector. The sides 9 of the remaining link connector are similarly connected with the normally open contacts of the lever springs 10 of the keys 5, 6, and 7 individual to this latter connector. Thus each line is provided with a pair of contact springs 10 for each link connector and each link connector is provided with normally open contacts for the springs 10 of the keys associated therewith. By depressing keys associated with the same link connector, lines individual to said keys may be connected.

Let it be assumed that station A is a calling station and that the trunk line No. 1 becomes, indirectly, a calling line. Let it also be assumed that the station C happens

to be the called station and the line 4 thereof the called line. The operator at exchange 2, in a well known way, effects the operation of a line signal 11. The operator at the private branch exchange where the keys 5, 6, and 7 are located depresses a key 5 individual to the calling line 1 and which is associated with an idle link connector 8, the extent to which the key is depressed being sufficient to enable said key to rock the trip 12 to a position in which it may escape the cam 13 and occupy a position above said cam to hold the depressed key in a position in which the sides of the line 1 will be connected with the sides 8 of the selected link connector through the intermediation of the contact springs 10 and the contacts provided for said springs. The portion 14 of the depressed key moves a bar 15 against the force of the bar restoring spring 15¹ in the plane of the bar to cause the pawl 16 to move the toothed wheel 17 one step to the right from the normal position of said toothed wheel (which normal position is shown at the lower one of the two wheels 17 in Fig. 2). The wheel 17 is fixed upon a shaft 18 that carries a cam 19. Upon the single step in the rotation of the shaft 18 accomplished by the depression of the actuated key 5, the cam 19 is caused to bring the springs 20 into engagement with their contacts which normally constitute the terminals of the operator's telephone outfit 21, the operator's telephone being bridged across the sides of the calling line 1 as a consequence of the engagement of the springs 20 with their contacts whereby the operator is informed of the wants of the calling subscriber. Assuming that the calling subscriber desires connection with station C, the operator will fully depress the key 7 associated with the selected link connector 8 and individual to the line 4 of the party to be called. The cam 14 will again operate the bar 15 to move the previously actuated star wheel 17 another step to remove the cam 19 from engagement with the spring mechanism 20 thereby to remove the springs 20 from their contacts to cut the operator's telephone out of circuit. When the key 7 individual to the called line has been fully depressed, the ringing circuit contacts 22 are closed to establish circuit through the ringing magnet 23, which circuit may be traced from that contact 22 which is directly grounded to the remaining contact 22, the winding of ringing magnet 23, the battery 24 to ground. The armature switches of magnet 23 are thereupon withdrawn from engagement with the normal contacts and are brought into engagement with the alternate contacts which are connected with the terminals of an alternating current generator 25.

Each of the lines of stations B and C has a ringing magnet 23, the sides of these lines

125

130

being connected with the armature switches of said magnet so that when said magnets are energized in the manner which has been described the generator 25 is included in circuit with the called line thereby to operate the signal receiver 26 at the station of the called line. Assuming that the actuated key 7 individual to the called line 4 is still fully depressed, a circuit is also established which 5 may be traced from the grounded battery 27, which may be the same battery 24 made common, through the resistance 28, the then engaged contacts 29, the marginal relay 30 (provided for a purpose to be stated) the 10 cut off relay 31 to ground. The armature switches of the cut off relay 31 are thus disengaged from their contacts that lead, one, direct to ground and the other to ground through a battery 32 (which may be the 15 same battery 24 made common with the batteries 27 and 32). The cut off relay 31 of the called line 4 when energized as described and shown, interrupts the circuit for the line signal 33 and prevents the operation of the 20 signal 33 by way of the armature switches of cutoff relay 31 when the party C responds. The battery circuit for the signal 33 includes the employed link connector and the battery 34 whereby the signal 33 acts as a supervisory signal to determine when the called 25 party responds. The battery 32 is only adapted to energize relay 33 as a line signal. As illustrated the signals 33 of the lines 3 and 4 serve not only to enable the stations 30 B, C to initiate calls but also serve to indicate to the operator that these stations have responded when they are called, and serve further to indicate to the operator that the 35 parties at stations B, C have restored their 40 telephones upon their switch hooks. That is, the signals 33 are not only line signals but are supervisory or disconnect signals as well. The circuit connections for the signal 33 that are normally furnished at the associate 45 cutoff relay 31 are replaced, where the trunk line is a calling line, by connections including the common battery 34 at the exchange 2, this battery being in bridge of the sides 1 of the trunk line and thereby being in bridge 50 of the sides 8 of the employed link connector and through these sides 8 in bridge between the sides of the called line 4.

If the station B were the calling station, the normal connections furnished for the 55 signal 33 of the called line at the cutoff relay would be replaced by the battery 35 (which could be merged with the batteries indicated at 24, 27 and 32) this battery 35 being included in circuit with the signal 33 by a 60 path which may be traced from the upper terminal of the battery 35, the winding of the relay 36, the uppermost armature switch of the relay 37 and the then engaged contact of such armature switch, the normally engaged contacts 38 of a key 39, a side 8 of the

employed link connector, the right hand spring 10 and its then engaged contact, one side of the line 4, the normally engaged contacts 40 of a listening key to be later described, the right hand armature switch of the ringing magnet 23 and its normal contact, one side of the line 4, the signal 33, the telephone equipment at the substation C, the other side of the line 4, the left hand armature switch of the ringing magnet 23, the 70 normally engaged contacts 41 of the aforesaid listening key, the left hand spring 10 of the selected key 7 associated with the link connector 8, the normally engaged contacts 42 of the key 39, the lowermost armature switch of relay 37 and its normally engaged contact, the impedance coil 43 to ground.

Assuming that the called party at station C who is connected by way of the trunk line 85 has responded, the signal 33 will be energized as a supervisory signal. When the called party restores his telephone upon its switch hook, the high resistance bridge including the signal receiver 26 is substituted 90 for the low resistance telephone bridge so that the signal receiver 33 is rendered inert, the signal device 33 thus acting fully to inform the operator of the condition of the called line. Where a local line, such as 95 either of the lines 3 and 4, is a calling line, the signal 33 will also serve to keep the operator informed of the condition of such line, such signal, when energized, then receiving its current from the battery 35. 100 After the operator has fully depressed the key 7 with the results which have been specified, she then releases said key so that the cam 13 will be engaged by the trip 12 to hold the key 7 in the position shown in Fig. 105 2 during an established connection, the cam 13 escaping the trip 12 when the key 7 has been lowered to or toward its ringing position so that said trip is in position to engage the cam 13 when the key 7 is partially returned to its normal idle position. It is understood that any key individual to the line 3 or the line 4 when such line is a calling line is depressed sufficiently to enable the cam 13 to escape the trip 12 but preferably 110 not sufficiently to include the ringing generator in circuit with the calling line.

When the star wheel 17 has been turned two steps to disengage the springs 20 from their contacts, the holding pawl 44 is moved 120 by the cam 45 to place it into engagement with a bar 46 to hold this bar in its normal position. Normally the bar 46 is free of the detent 44, this bar being provided with a recess 47 for each of the keys 5, 6 and 7, this recess at each key being normally so positioned that the bar 46 will be engaged by the cam 14 when such key is depressed to effect a slight movement of the bar 46 to the left against the force of a spring 48, the normal 130

disconnection of the detent 44 permitting the movement of the bar 46 by an engaging cam 14 and permitting the return movement of said bar by the spring 48. When, 5 however, the bar 46 is locked in position by the detent 44, which occurs when two keys associated with said bar have been operated to connect a calling and called line, no further key associated with said bar can be depressed whereby no other line may be connected with lines previously connected and whereby the operator's telephone set cannot be included in circuit with these previously connected lines, which could be done 10 were she permitted to step the shaft 18 around farther.

I have now described how a calling party secures connection with a called party and have specifically referred to apparatus associated with one of the lines which has been chosen to represent a calling line, and have specifically described apparatus associated with a line chosen to represent a called line. A large number of devices are illustrated 20 having similar functions and possessing similar parts, and I will therefore apply reference characters to similar parts of the equipment which have similar functions. In the case of the trunk keys 5, a slight distinction happens to exist, in the embodiment of the invention illustrated, as compared with the local line keys 6 and 7. The normally separated left hand contacts 49 are included in a circuit normally open at 25 said contacts and which circuit may be traced from the grounded battery 50 which may be merged with the batteries 24, 27 and 32, through the contacts 49, the grounded relay 51, the relays 51 and 30 being provided for similar purposes, each to be unresponsive when but one key of the line to which it is individual is actuated. If another key, individual to such line, is actuated then the flow of current through the 30 relays 51 or 30 will be sufficiently increased to enable such relay to be energized to establish circuit at 52 to establish a short circuit across the associate line whereby the voice currents are shunted so that no line 35 may intrude. The contacts 53 may also be closed to operate an alarm 54 to notify some one in authority that the exchange is not being properly operated. By the guard afforded at 52 the operator is prevented from 40 using an idle link connector for connecting her telephone set in circuit with an established connection and from connecting a third party in circuit with an established connection. Each of the trunk circuit keys 45 5 is provided with a pair of normally separated contacts 55 in a normally open circuit which may be traced from a battery 56 (that may be merged with batteries 24, 27, 32 and 50) the contacts 55, the conductor 60 65 8, the winding of cutoff relay 37 to ground,

this cutoff relay 37 being peculiar only to the trunk keys. When the relay 37 is energized the battery 35 is removed to enable the use of the battery 34 free from other battery influence, this battery 34 supplying the telephonic current in place of the battery 35 which is employed to supply such current when local lines are connected. 70

To prevent the operator from using keys of different link connectors for bringing her telephone into circuit with a connection established by such link connectors I provide contacts 20¹ which are closed when the springs 20 engage their contacts. The contacts 20¹, when closed, establish circuit 80 through the magnet 20² which circuit may be traced from the grounded terminal of said magnet through the engaged contacts 20¹, the normally engaged contacts 20³, the resistance coil 20⁴, and the grounded battery 20⁵. The resistance of the magnet 20² is such, however, that it will not be energized when but one pair of contacts 20¹ is closed but will be energized when two pairs of contacts 20¹, pertaining to the keys that are 90 actuated by the operator in the effort to listen in, are closed. It is understood that when an operator thus employs two keys of different link connectors in an endeavor to listen in on an established connection she 95 will cause the star wheels 17 individual to such employed keys to move each one step only from normal whereby contacts are closed at 20, 20¹, whereby the relay 20² will receive current supplied thereto through the 100 two resistances 20⁴ that are in parallel with each other and in serial relation with the relay 20² whereupon the relay 20² will receive sufficient current to prevent the telephonic connection of the operator's set in 105 the established circuit. When the magnet 20² is energized a low resistance shunt is closed at its left hand armature switch across the sides of the operator's telephone 110 circuit. This shunt connection joins springs 20 and thereby prevents a third station from listening in upon an established connection by means of any circuits the operator may be able to establish. The right hand armature switch of the magnet 20² will, when 115 said magnet is sufficiently energized as described, operate the signal 54 for the purpose hitherto stated.

The trips 12 are pivotally mounted at their elbows upon a common bar 57 which is provided for closing a pair of contacts 58 when the bar 57 is moved against the force of its restoring spring 59 by the engagement of the cam 13 of an actuated key with a finger 60 carried by the bar, this finger 60 being engaged by such cam 13 to maintain the closure of the contacts 58 until the parts are restored to normal. Assuming that two local lines such as those of stations B and C have been connected and are through, the 120 125 130

relay 36 will be deenergized when the telephone receivers at both local stations are restored upon their switch hooks. The magnet 61, which was previously energized over a local circuit established by the relay 36, is included in open circuit so that its armature may engage its contact thereby to establish a circuit which may be traced from the grounded battery 62 through the armature switch and contact of relay 61, the magnet 63, the magnet 64, the contacts 58 to ground. The magnet 64 thereupon withdraws the holding pawl 65 which is provided to maintain star wheel 17 in any position to which it is placed, whereupon the restoring spring 66 operates to restore the star wheel 17 and the shaft 18 to normal, this normal position being illustrated at the lower star wheel 17 in Fig. 2. The magnet 63 is in the association illustrated in Figs. 5, 6, and 7. When it is energized its armature, which is in engagement with angular extensions of the bars 46, 15 and 57, rocks said bars away from the keys so that said keys may be thrust to their uppermost positions by the coil springs illustrated at the lower ends thereof, whereupon circuit is opened at 58 and the armature of magnet 63 is restored, the entire apparatus then being in normal position.

Where one of the lines is a trunk line I desirably provide a finger 67 upon the rod 57 so that circuit through a magnet 68 may be established by the closure of contacts 69 when the bar 57 is moved to the right. The armature of the magnet 68 maintains circuit through said magnet, which circuit includes the sides of the trunk line 1, the battery 34 in bridge or said sides, portions of the sides of the link connector 8 and the relay 68, another magnet 69¹ being serially included in a portion of one of the sides of the link connector in serial relation with the relay 68. The magnet 68 acts to maintain circuit for the magnet 69¹ and also serves to prevent a change, prior to the response of the called party, in the supervisory apparatus at the exchange 2, the magnet 68 being of sufficiently high resistance to enable it to be shunted by the called party's telephone so that the supervisory signal at the trunk end of the link connector at the calling exchange 2 may be under the control of the telephone at the called station, the magnet 68 then being out of circuit. The circuit of the relay 69¹, however, remains intact, a connection in place of that afforded by the armature switch of relay 68 being furnished by the switch hook and telephone bridge at the called station. The armature switch of relay 69¹ when attracted, serves to establish the circuit which may be traced from ground through said armature switch over conductor 8² through relay 61 and the grounded battery 62, with the result that the armature switch of the magnet 61 is attracted to hold

the circuit through the magnets 63 and 64 open, the magnet 69¹, when associated with the trunk circuit, thus performing the function of the magnet 36 when this magnet 36 is associated with two connected local lines. 70 When the circuit for the magnet 69¹ is opened, which is usually done at the called station by the restoration of the telephone receiver upon its switch hook, the magnet 61 is deenergized and the magnets 63 and 64 are energized with results which have been described. 75

When the trunk line 1 is automatically constituted a continuation of a telephone line, as for example by the equipment illustrated in Fig. 3, the magnet 68 serves to prevent the premature release of the trunk line 1, the shunt which is established by the magnet 68 at its armature switch for this purpose being replaced by the low resistance bridge which is established at the called station, when the party at the called station responds. 85

A key 39 is individual to each link circuit, these keys being shown in normal position. 90 The shanks of the keys pass through enlarged openings in the bars 15 and 46, these bars having no mechanical relation with said key. Each key 39 is provided with a cam 13 coöperating with the trip 12 similarly to the coöperation of the other cams 13 with the trip 12 associated therewith. The keys 39 enable the operator to exclude her telephone set from circuit with a calling line without connecting another line with such calling line and when the operator wishes to do this she depresses the selected key 39 until the trip 12 is engaged by the cam 13 thereby to maintain the contacts 42 and 38 open. When the parts are restored to normal by the operation of the magnets 63 and 64 which has been described, any key 39 that has been depressed will be restored to normal. 95

I also desirably provide listening keys 69², each individual to a line entering the exchange and mechanically independent of the link connector equipment which I have previously described. These individual keys are so interrelated that they cannot be manipulated to permit an operator to listen in on an established connection nor to permit an additional line to become connected with an established connection, this feature of my invention being of importance irrespective of the mechanism which is employed to connect telephone lines in conversation. These individual keys 69² are to be used in the event of an unexpected number of connections desired by way of the exchange and enables the operator to inform the subscribers that the facilities of the exchange cannot for the time being permit of connections desired. To prevent the operators from listening in upon an established connection and to prevent other lines from be- 100 105 110 115 120 125 130 135

- coming connected with an established connection, I establish a low resistance bridge connection which may be traced from the conductor 70 to the conductor 71 by way of the armature switch of the marginal relay 72. When but one listening key 69² is depressed enough current will not pass through the relay 72 to operate its armature switches. When two keys are depressed, current is sufficiently increased through the marginal relay 72 to permit its operation with the result described. Circuit establishable by each of the keys 69² through the relay 72 may be traced from each of the grounded batteries 73 through the resistance 74, the then engaged contacts 75, the conductor 76, the magnet 77, the marginal relay 72 to ground. The magnet 72 is provided with an upper armature switch that serves when operated to actuate the signal 54 for the purpose previously described. The magnet 77 is energized when any key 69² is depressed for the purpose of removing the connections that intervene between the operator's telephone 21 and the contacts 20, etc., and serve to connect said telephone 21 with the conductors 70 and 71 with the operator's telephone 21 and the normally open contacts of the listening keys 69². Each key 69² is provided with serially related contacts that are interposed between the lines and the link connectors so that when any key 69² is operated it will serve to prevent the operator from listening in upon established connections. Talking battery is furnished at 78 to the stations of local telephone lines and to the operator's set 21 when a key 69² is depressed. The condensers 79 are included in the conductors 70 and 71 between the keys of the local lines and the keys of the trunk line to prevent the battery 78 from interfering with the signals at exchange 2. A high resistance impedance coil 80 is included in bridge between the conductors 70 and 71 to enable the operator to signal exchange 2 and to prevent faulty operation of the signal apparatus at the trunk end of the link circuit shown at exchange 2.
- If the operator should desire to restore the keys 5, 6 and 7 manually she may do so by manipulating the keys 81, one such key being individual to each link connector, the key 81 being shown in Figs. 1 and 8. This key has a wedge or cam 82 that serves to rotate the bars 45, 46 and 57 in a manner similar to the rotary effect of the magnet 63, the position to which these bars may be moved being indicated in Fig. 6 whereafter the link connector keys will automatically be restored to normal as has been described.
- While I have herein shown and particularly described the preferred embodiment of my invention I do not wish to be limited to the precise details of construction and circuit arrangement shown as changes may readily be made without departing from the spirit of my invention.
- Having thus described my invention I claim as new and desire to secure by Letters Patent the following:
1. A telephone exchange system including a plurality of telephone lines extending to an exchange; a plurality of link connectors for joining said lines in telephonic connection; a plurality of switches for each link connector, each switch being individual to a telephone line, these switches having contacts and circuit connections that enable them to connect the lines to which they are individual with the link connector to which they are common whereby lines may be telephonically connected; and an operator's telephone provided with circuit connections governed by said switches and serving to enable the telephonic connection thereof with the telephone lines. 70
2. A telephone exchange system including a plurality of telephone lines extending to an exchange; a plurality of link connectors for joining said lines in telephonic connection; a plurality of switches for each link connector, each switch being individual to a telephone line, these switches having contacts and circuit connections that enable them to connect the lines to which they are individual with the link connector to which they are common whereby lines may be telephonically connected; an operator's telephone provided with circuit connections governed by said switches and serving to enable the telephonic connection thereof with the telephone lines. 75
3. A telephone exchange system including a plurality of telephone lines extending to an exchange; a plurality of link connectors in interchangeable relation to calling lines and in interchangeable relation to called lines for joining said lines in telephonic connection; a plurality of operator controlled switches for and individual to each link connector, each switch being individual to and permanently associated with a telephone line, these switches having contacts and circuit connections that enable them to connect the lines to which they are individual with the link connector to which they are common whereby lines may be telephonically connected; and means jointly controlled by the switches that connect calling and called lines with the same link connector for preventing the connection of an additional telephone line with this link connector. 80
4. A telephone exchange system including a plurality of telephone lines extending to an exchange; a plurality of link connectors in interchangeable relation to calling 85

lines and in interchangeable relation to called lines for joining said lines in telephonic connection; a plurality of operator controlled switches for and individual to 5 each link connector, each switch being individual to and permanently associated with a telephone line, these switches having contacts and circuit connections that enable them to connect the lines to which they are 10 individual with the link connector to which they are common whereby lines may be telephonically connected; and mechanical means jointly controlled by the switches that connect calling and called lines with the same 15 link connector for mechanically preventing such operation of an additional switch associated with this link connector that would connect the telephone line to which this additional switch is individual with this link 20 connector.

5. A telephone exchange system including a plurality of telephone lines extending to an exchange; a plurality of link connectors in interchangeable relation to calling 25 lines and in interchangeable relation to called lines for joining said lines in telephonic connection; a plurality of switches for and individual to each link connector, each switch being individual to and permanently associated with a telephone line, these switches having contacts and circuit 30 connections that enable them to connect the lines to which they are individual with the link connector to which they are common 35 whereby lines may be telephonically connected; and means jointly controlled by switches that connect calling and called lines with the same link connector for preventing inclusion of the operator's telephone in connection with the connected lines. 40

6. A telephone exchange system including a plurality of telephone lines extending to an exchange; a plurality of link connectors in interchangeable relation to calling lines 45 and in interchangeable relation to called lines for joining said lines in telephonic connection; a plurality of switches for and individual to each link connector, each switch being individual to and permanently associated with a telephone line, these switches having contacts and circuit 50 connections that enable them to connect the lines to which they are individual with the link connector to which they are common whereby 55 lines may be telephonically connected; and mechanical means jointly controlled by the switches that connect calling and called lines with the same link connector for mechanically preventing the inclusion of the 60 operator's telephone in connection with the connected lines.

7. A telephone exchange system including a plurality of telephone lines extending to an exchange; a plurality of link connec-

tors for joining said lines in telephonic connection; a plurality of switches for each link connector, each switch being individual to a telephone line, these switches having contacts and circuit connections that enable them to connect the lines to which they are individual with the link connector to which they are common whereby lines may be telephonically connected; and means jointly controlled by switches of different link connectors for preventing the inclusion of the 75 operator's telephone in connection with connected lines. 77

8. A telephone exchange system including a plurality of telephone lines extending to an exchange; a plurality of link connectors 80 in interchangeable relation to calling lines and in interchangeable relation to called lines for joining said lines in telephonic connection; a plurality of switches for and individual to each link connector, each 85 switch being individual to and permanently associated with a telephone line, these switches having contacts and circuit connections that enable them to connect the lines to which they are individual with the link 90 connector to which they are common whereby lines may be telephonically connected; and means jointly controlled by switches associated with the same link connector for preventing inclusion of the operator's telephone in connection with connected lines. 95

9. A telephone exchange system including a plurality of telephone lines extending to an exchange; a plurality of link connectors for joining said lines in telephonic connection; a plurality of switches for each link connector, each switch being individual to a telephone line, these switches having contacts and circuit connections that enable them to connect the lines to which they are individual with the link connector to which they are common whereby lines may be telephonically connected; and means jointly controlled by the switches of different link connectors for preventing the connection of 100 a telephone line with connected lines.

10. A telephone exchange system including a plurality of telephone lines extending to an exchange; a plurality of link connectors in interchangeable relation to calling 115 lines and in interchangeable relation to called lines for joining said lines in telephonic connection; a plurality of operator controlled switches for and individual to each link connector, each switch being individual to and permanently associated with a telephone line, these switches having contacts and circuit connections that enable them to connect the lines to which they are individual with the link connector to which they are common whereby lines may be telephonically connected; and means jointly controlled by the switches associated with the 120

125

same link connector for preventing the connection of a telephone line with connected lines.

11. A telephone exchange system including a plurality of telephone lines extending to an exchange; means for connecting these lines for conversation; operator's listening switches individual to the lines; and means jointly controlled by a plurality of listening switches for effectively excluding the operator's telephone from circuit with connected lines.

12. A telephone exchange system including a plurality of telephone lines extending to an exchange; means for connecting these lines for conversation; operator's listening switches individual to the lines; and means jointly controlled by a plurality of listening switches for effectively excluding an additional telephone line from connection with connected lines.

13. A telephone exchange system including a plurality of telephone lines extending to an exchange; a second exchange, one of the aforesaid lines being a trunk line extending from the second exchange to the first exchange; a plurality of link connectors at the first exchange for joining said lines in telephonic connection; a plurality of switches for each link connector, each switch being individual to a telephone line, these switches having contacts and circuit connections that enable them to connect the lines to which they are individual with the link connector to which they are common, whereby lines may be telephonically connected; means associated with the link connectors for preventing alteration of the operative condition of the equipment at the second exchange associated with the trunk line when a call is initiated at the second exchange for a line entering the first exchange and prior to the response of the called party; and means at the called station whose line extends to the first exchange for removing the influence of the aforesaid means to enable the party at the called station to change the operative condition of said equipment at the second exchange.

14. A telephone exchange system including a plurality of telephone lines extending to an exchange; a plurality of link connectors in interchangeable relation to calling lines and in interchangeable relation to called lines for joining said lines in telephonic connection; a plurality of operator controlled switches for and individual to each link connector, each switch being individual to and permanently associated with a telephone line, these switches having contacts and circuit connections that enable them to connect the lines to which they are individual with the link connector to which they are common whereby lines may be telephonically connected; and mechanism oper-

able by conjoint action of two switches associated with each link connector to prevent the effective operation of a third switch associated with the link connector.

15. A telephone exchange system including a plurality of telephone lines extending to an exchange; a plurality of link connectors in interchangeable relation to calling lines and in interchangeable relation to called lines for joining said lines in telephonic connection; a plurality of switches for and individual to each link connector, each switch being individual to and permanently associated with a telephone line, these switches having contacts and circuit connections that enable them to connect the lines to which they are individual with the link connector to which they are common whereby lines may be telephonically connected; and means operable by the switch of a called party to exclude the operator's telephone from circuit.

16. A telephone exchange system including a plurality of telephone lines extending to an exchange; a plurality of link connectors in interchangeable relation to calling lines and in interchangeable relation to called lines for joining said lines in telephonic connection; a plurality of switches for and individual to each link connector, each switch being individual to and permanently associated with a telephone line, these switches having contacts and circuit connections that enable them to connect the lines to which they are individual with the link connector to which they are common whereby lines may be telephonically connected; and means jointly controlled by the switches of calling and called parties for excluding the operator's telephone from circuit.

17. A telephone exchange system including a plurality of telephone lines extending to an exchange; a plurality of link connectors in interchangeable relation to calling lines and in interchangeable relation to called lines for joining said lines in telephonic connection; a plurality of switches for and individual to each link connector, each switch being individual to and permanently associated with a telephone line, these switches having contacts and circuit connections that enable them to connect the lines to which they are individual with the link connector to which they are common whereby lines may be telephonically connected; means operable by the switch of a called party to exclude the operator's telephone from circuit; and switches for excluding calling lines from circuit with the operator's telephone.

18. A telephone exchange system including a plurality of telephone lines extending to an exchange; a plurality of link connectors in interchangeable relation to call-

- ing lines and in interchangeable relation to called lines for joining said lines in telephonic connection; a plurality of switches for and individual to each link connector, each switch being individual to and permanently associated with a telephone line, these switches having contacts and circuit connections that enable them to connect the lines to which they are individual with the link connector to which they are common whereby lines may be telephonically connected; means jointly controlled by the switches of calling and called parties for excluding the operator's telephone from circuit; and switches for excluding calling lines from circuit relation with the operator's telephone. 10 70 75
19. A telephone exchange system including a plurality of telephone lines extending to an exchange; a plurality of link connectors in interchangeable relation to calling lines and in interchangeable relation to called lines for joining said lines in telephonic connection; a plurality of switches for and individual to each link connector, each switch being individual to and permanently associated with a telephone line, these switches having contacts and circuit connections that enable them to connect the lines to which they are individual with the link connector to which they are common whereby lines may be telephonically connected; switching mechanism for each link connector for including the operator's telephone in circuit relation with calling lines; and means governed by the switches of the calling and called lines for operating the switching mechanism two steps, the first step being effected by the switch of a calling line to include the operator's telephone in circuit and the second step being effected by the switch of the called line to exclude the operator's telephone from circuit. 15 80 85 90 95 100
20. A telephone exchange system including a plurality of telephone lines extending to an exchange; a plurality of link connectors in interchangeable relation to calling lines and in interchangeable relation to called lines for joining said lines in telephonic connection; a plurality of switches for and individual to each link connector, each switch being individual to and permanently associated with a telephone line, these switches having contacts and circuit connections that enable them to connect the lines to which they are individual with the link connector to which they are common whereby lines may be telephonically connected; and means jointly controlled by switches of different link connectors for preventing the inclusion of the operator's telephone in connection with connected lines. 105
22. A telephone exchange system including a plurality of telephone lines extending to an exchange; a plurality of link connectors for joining said lines in telephonic connection; a plurality of switches for each link connector, each switch being individual to and permanently associated with a telephone line, these switches having contacts and circuit connections that enable them to connect the lines to which they are individual with the link connector to which they are common whereby lines may be telephonically connected; and means jointly controlled by switches of different link connectors for preventing the inclusion of the operator's telephone in connection with connected lines. 110
23. A telephone exchange system including a plurality of telephone lines extending to an exchange; a plurality of link connectors for joining lines in telephonic connection; a plurality of switches for each link connector, each switch being individual to and permanently associated with a telephone line, these switches having contacts and circuit connections that enable them to connect the lines to which they are individual with the link connector to which they are common whereby lines may be telephonically connected; and means jointly controlled by the switches of different link connectors for preventing the connection of a telephone line with connected lines. 115
24. A telephone exchange system including a plurality of telephone lines extending to an exchange; means for connecting these lines for conversation; operator's listening switches individual to and permanently associated with the lines; and means jointly controlled by a plurality of listening switches for effectively excluding the operator's telephone from circuit with connected lines. 120 125
25. A telephone exchange system including a plurality of telephone lines extending to an exchange; means for connecting these lines for conversation; operator's listening 130

switches individual to and permanently associated with the lines; and means jointly controlled by a plurality of listening switches for effectively excluding an additional telephone line from connection with connected lines.

26. A telephone exchange system including a plurality of telephone lines extending from subscribers' stations to an exchange; a plurality of link connectors in interchangeable relation to calling lines and in interchangeable relation to called lines for joining said lines in telephonic connection; a plurality of switches for and individual to each link connector, each switch being individual to and permanently associated with a telephone line, these switches having contacts and circuit connections that enable them to connect the lines to which they are individual with the link connector to which they are common whereby lines may be telephonically connected; and subscriber station controlled means for restoring actuated switches to normal.

25. 27. A telephone exchange system including a plurality of telephone lines extending from subscribers' stations to an exchange; a plurality of link connectors in interchangeable relation to calling lines and in interchangeable relation to called lines for joining said lines in telephonic connection; a plurality of switches for and individual to each link connector, each switch being individual to a telephone line, these switches having contacts and circuit connections that enable

them to connect the lines to which they are individual with the link connector to which they are common whereby lines may be telephonically connected; and subscriber station controlled means for restoring actuated 40 switches to normal.

28. A telephone exchange system including a plurality of telephone lines extending to an exchange; a plurality of link connectors for joining said lines in telephonic connection; a plurality of keys for each link connector, each key being individual to a telephone line, these keys having contacts and circuit connections that enable them to connect the lines to which they are individual with the link connector to which they are common, whereby lines may be telephonically connected; an operator's telephone; a plurality of operator's keys for interchangeably associating the operator's 50 telephone with link connectors; means for holding said operator's keys in actuated positions; and means common to and in actuating relation with the aforesaid means, the operator's keys operating upon the first 60 aforesaid means to operate the second aforesaid means whereby an operator's key in being depressed will effect the restoration of a previously depressed operator's key.

In witness whereof, I hereunto subscribe 65 my name this 24th day of July, A. D. 1911.

MORTON L. JOHNSON.

Witnesses:

E. L. WHITE,
G. L. CRAGG.
